(57) **CLAIM**

The ornamental design for an electronic device mount adapter, as shown and described.

DESCRIPTION

FIG. 1 is a perspective view of an electronic device mount adapter, showing my new design;

FIG. 2 is a right side elevation view thereof;

FIG. 3 is a left side elevation view thereof;

FIG. 4 is a top plan view thereof;

FIG. 5 is a bottom plan view thereof;

FIG. 6 is a front elevation view thereof;

FIG. 7 is a rear elevation view thereof;

FIG. 8 is a perspective view of the electronic device mount adapter of FIG. 1, shown attached to an additional environmental electronic device;

FIG. 9 is a right side elevation view thereof;

FIG. 10 is a left side elevation view thereof;

FIG. 11 is a top plan view thereof;

FIG. 12 is a bottom plan view thereof;

FIG. 13 is a front elevation view thereof; and,

FIG. 14 is a rear elevation view thereof.

Broken lines showing an environmental electronic device in FIGS. 8-14 depict unclaimed environment and form no part of the claimed design. All other broken lines seen in the drawings depict portions of the electronic device mount adapter that form no part of the claimed design.

FIGS. 1-7 and FIGS. 8-14 show the design in alternate configurations for illustration purposes only.
